[57] CLAIM

The ornamental design for a combined scissors with cap, as shown and described.

DESCRIPTION

FIG. 1 is a front elevational view of a combined scissors with cap showing my new design, the opposite side being a mirror image;

FIG. 2 is a top plan view thereof;

FIG. 3 is a right side elevational view thereof, the opposite side being a mirror image;

FIG. 4 is a bottom plan view thereof;

FIG. 5 is a front elevational view thereof with the cap removed for clarity of illustration, the opposite side being a mirror image;

FIG. 6 is a top plan view of FIG. 5;

FIG. 7 is a bottom plan view of FIG. 5;

FIG. 8 is a side elevational view of FIG. 5; and

FIG. 9 is an exploded perspective view thereof.

FIG. 6

FIG. 2

FIG. 5
